INVENTOR

A. T. Brown

UNITED STATES PATENT OFFICE.

ALEXANDER T. BROWN, OF SYRACUSE, NEW YORK, ASSIGNOR TO PETER BURNS, OF SAME PLACE.

LOCK FOR FIRE-ARMS.

SPECIFICATION forming part of Letters Patent No. 234,749, dated November 23, 1880.

Application filed October 2, 1880. (Model.)

To all whom it may concern:

Be it known that I, ALEXANDER T. BROWN, of Syracuse, in the county of Onondaga and State of New York, have invented certain new and useful Improvements in Locks for Fire-
5 Arms, and that the following, in connection with the accompanying drawings, is a full description thereof.

My invention relates particularly to locks
10 for three-barreled guns of the character de-
scribed in W. H. Baker's Patents, Nos. 167,293,
dated the 31st day of August, 1875, and
198,333, dated the 18th day of December, 1877,
in which a rifle-barrel is arranged below and
15 between the barrels of a double-barreled shot-
gun; and it consists of an inside hammer piv-
eted in the trigger-plate and working between
the side locks, and provided with means by
which it may at pleasure be connected with
20 the tumbler of one of the side locks, and thus
be operated by the mainspring of said side
lock; or, when so connected and it is found
desirable to fire the shot-barrel first, that it
may be easily disconnected. In this manner
25 I simplify the lock by dispensing entirely with
the mainspring, a sear, and sear-spring for the
lock of the rifle-barrel.

Referring now to the drawings, Figure 1 is a
30 side view of the frame of the gun with the
right-hand lock removed, showing the mech-
anism of the left-hand and inside locks. Fig.
2 is a view of the inside hammer and its piv-
eted hook; and Fig. 3 is a view of the lower
35 part of the outside hammer and its tumbler.

a indicates the outside hammer; *b*, its tum-
bler; *c*, an arm projecting from said tumbler
b, and provided at its end with a projecting
pin or screw, *d*. *e* is the inside hammer, piv-
40 oted in an opening in the trigger-plate, as
shown in Fig. 1, and *f* is a hook pivoted to
said hammer *e* in rear of the pivot of the lat-
ter. *j* is the comb or finger-piece of the ham-
mer *e*, which extends below the trigger-plate,
and by which the hammer *e* is cocked. *m* is a
45 link to which the mainspring *g* of the side lock
is connected, the lower end of said link being
connected to the tumbler *b* in the manner de-
scribed in W. H. Baker's Patent, No. 199,773,
dated the 29th day of January, 1878. *i* is the

sear which engages with the tumbler *b*. *h* is 50
a spring, arranged on the under side of the
tang of the frame so as to bear on the ham-
mer *e* and hold it by frictional contact either
in its cocked or uncocked position, so as to
secure certainty of action. 55

The operation of this mechanism is as fol-
lows: When it is desired to fire the rifle-bar-
rel the outside hammer is first full-cocked.
By this operation the arm *c* is carried down
into a position to be engaged by the hook *f*. 60
The hammer *e* is then cocked by pressing
against the finger-piece *j*. In this operation
the pivotal point of the hook is carried down-
ward, and the rear edge or side of said hook
comes in contact with the end of the opening 65
in which the hammer is pivoted, and is there-
by turned forward so as to bring the hook in
the line of travel of the pin *d* on the arm *c*,
and these parts are engaged and the hammer
70 *e* is carried forward by the force of the main-
spring *g*, and caused to strike its firing-pin.

The length of the hook *f* is such that when
the hammer *e* is arrested the hammer *a* will
not have finished its stroke, and will be pre-
vented from striking its firing-pin, and the 75
rifle-barrel will alone be fired. When, how-
ever, it is desired to fire the shot-barrel the
hammer *e* is not cocked, and the hook will
then not engage the arm *c*, and then hammer
80 *a* will be free to fall, or, the hammers having
been brought into engagement with each other,
they may be disconnected by letting the ham-
mer *a* down and then recocking it. This will
leave the hammer *e* in its uncocked position,
and the hook will not engage the arm *c* when 85
the hammer *a* is discharged.

It is evident that instead of relying on the
end of the opening in the trigger-plate to move
the hook into position to engage the arm *e*, a
pin or stud may project from the lock-plate, 90
and that the arm *c* may be arranged on the
tumbler of either of the side locks.

Having thus described my invention, what
I claim as new is—

1. In a gun-lock of the character described, 95
the combination of an inside hammer pivoted
in the trigger-plate and provided with a pivoted
hook, as shown, and the hammer and tumbler of

the side lock, the parts being arranged to be connected and disconnected substantially in the manner and for the purpose described.

2. The combination of the hammer *a* and tumbler *b*, provided with arm *c* and pin *d*, the hammer *e* and its pivoted hook *f*, arranged to be connected with and disconnected from the arm *c* and pin *d* in the manner substantially

as described, whereby either the inside or outside hammer may be actuated by the same mainspring, as described.

ALEXANDER T. BROWN.
